UNITED STATES PATENT OFFICE.

JOHN T. A. PADDENBURG, OF BROOKLYN, NEW YORK, ASSIGNOR TO THE JOHN C. POWERS COMPANY, INC., OF NEW YORK, N. Y., A CORPORATION OF NEW YORK.

METHOD OF EMBOSSED.

Application filed August 25, 1923. Serial No. 659,289.

It has been proposed to produce simulations of cloth and like objects by embossing the same on paper or cardboard, but in the production of these simulations it has been the practice to produce a plate or die by etching and engraving on the same a representation of the texture of the cloth or other object which it is desired to reproduce. The exactness, however, of this simulation depends on the skill of the artist who etches or engraves the die, and consequently the replica is not a true reproduction of the object.

My invention contemplates the production of a replica which is an actual simulation of the object, and which does not depend upon the skill of an artist for the truth of its reproduction. I attain this result by the use of the actual object itself in the method of producing its replica.

The production of the replica by my means is broadly accomplished by forming a mold or female die from the object to be reproduced, and using this die in connection with a pliable and male die in the actual reproduction of the replica on paper or cardboard.

In the drawing I have illustrated a replica of a slab of stucco (Figure 1 being a plan view and Figure 2 a cross section), inasmuch as the invention is admirably adapted for such work in that it shows the exact design and texture of the stucco. It, however, is to be understood that I do not confine my invention to use in connection with the reproduction of stucco, for it is quite obvious that it can be used in the production of replicas of various other objects.

The replica itself consists of a sheet or plaque of paper or cardboard, sufficiently soft to permit embossing without cracking, on which the design of the object is impressed. For instance, in the case illustrated in the drawing, where the replica is that of a slab of stucco, the paper plaque 1 carries the embossed replica of the stucco, showing a reproduction of the trowel marks 2, with the ridges and vales, and showing also the actual texture of the surface of the stucco where, for instance, at 3 a stippled effect is produced by the effect of the grains of sand.

I have used several methods of producing the embossing of the object from the object itself, and I will enumerate three of

these, the last of which I consider the preferable.

Assuming that it is desired to produce a replica of a slab of stucco such as illustrated in the drawing, I have found it possible to 60 make an impression from the surface to be reproduced on a waxed sheet of brass. This wax is covered with a suitable metallizing medium such as graphite so as to establish an affinity for the metal which is later precipitated thereon. This sheet of brass, with the graphite-covered wax impression thereon, is then suspended in an electro-metal bath for a sufficient length of time to permit the formation of a metal shell thereon. 70 While there is no definite time for this suspension, as it is to be determined by experimentation and by the strength of the bath and other features, it usually takes from four to five hours for the proper amount 75 of metal to deposit thereon to produce a shell of sufficient thickness to have the necessary rigidity for subsequent use.

When this desired thickness has been obtained the shell is detached from the wax 80 form and is backed up with metal. This shell represents a facsimile in metal of the original surface of which it is desired to make a replica inasmuch as the wax was in effect a negative and the metal deposited 85 thereon in shell form therefore became a positive. The object of making this metal positive is so that a master model stronger and harder than the object itself may be obtained for subsequent use so that it will 90 stand up under repeated impressions. A wax impression is made of this metal positive or shell and this wax impression, being again a negative impression, is coated with graphite or other metallizing medium and 95 an additional shell is made in the same manner as before, that is to say, by submerging the same in an electro-metal bath and precipitating the desired amount of metal thereon. But the shell thus obtained from this 100 last precipitation is backed up with metal and used as a female die in the subsequent embossing operation.

A second method of producing the female die which I have found possible is to make a 105 plaster cast from the object of which the embossed replica is to be made, instead of making the first facsimile metal shell of the hereinbefore described method. When this plaster cast is made, an impression is made 110

of this on a waxed sheet of brass and the wax covered with graphite. This wax and graphite covered impression is then submerged in an electrometal bath as before until the proper thickness of metal plate has built up thereon. The metal plate thus produced is backed up as in the first case with metal and used as the female die for the subsequent embossing operation.

10 While I have found the two above described methods satisfactory, I find the following, or third, to be the most desirable. In this method the object of which it is desired to make the embossed replica is subjected to capillary attraction in a solution of gutta percha and bi-sulphite, or in similar solutions used for this purpose. I have found that in the reproduction of objects such, for instance, as the production of a 20 replica of a slab of stucco where the surface is exceedingly uneven, that there is considerable overhanging material which produces in effect undercuts. These undercuts, if reproduced in the female die, would, when the 25 die is used to produce the embossed replica, prevent a clean release of the impression, that is to say, of the replica, and would produce in many cases tearing of the paper or cardboard, and, in fact, the production of a 30 design not truly a replica of the object itself, owing to the distortion caused by the freeing of the paper from the die.

To overcome this difficulty I fill in the undercut places on the object, producing in 35 effect vertical walls, or at least walls which are not undercut. This I have successfully accomplished by filling in the overhangs or undercuts with wax and burnishing off this wax by means of suitable tools heated to 40 such a degree that the wax will be worked into the undercuts but will not be liquefied to such an extent that it will flow.

To the object thus impregnated, with the 45 undercuts filled with the wax, or with other suitable filler as described, I then apply graphite or other suitable metallizing medium, and suspend the same in an electro-metal bath. This results in the production of a shell the thickness of which is determined as before by the strength of the bath 50 and the length of time which the object remains in the bath.

This shell is then trimmed to the desired 55 size and is set in an electrotype or brass frame of the desired width which frame is in the illustrated instance of a smooth surface and slightly raised above the surface of the shell, so that when the plate is put through the press there will in effect be 60 formed an impressed replica of the slab of stucco with a smooth border surrounding the same.

Whether the female die is formed by the last and preferred method, or by either of 65 the other two methods, the die is attached to

a plate in a press so arranged that it may be heated by suitable means such as steam, gas or electricity. A piece of cardboard cut to the approximate size of the die is secured to the platen of the press, as, for instance, 70 by gluing, and an impression is made on this cardboard which, because it follows all of the conformations of the female die, becomes the counter or the male die, the conformation being facilitated by the heating 75 of the die.

When this cardboard or male die has cooled and hardened, it is ready to be used for the embossing operation. The paper which is fed into the press passes between 80 the two dies and when the same come together is forced into the crevices of the female die by the pressure of the male die and thus takes the impression and forms a true replica of the object to be produced. 85

In the case of the cement slab, it not only shows the trowel marks, but it also shows the texture of the stucco itself. The conformation of the paper as it is fed between the dies is facilitated by the heat in the 90 female die, which softens the fibers of the paper and allows the conformation to take place without breaking the fiber.

It will be seen that by using the stucco slab in the production of the male die, and by using the male die for the formation of the female die, a true embossed replica of the object is produced with all of the irregularities, texture, and design truly reproduced. 100

I claim:

1. The method of forming a die from an object, which consists in saturating the object with a solution of gutta percha and bi-sulphite, filling in any undercuts on said 105 saturated object, coating the surface of the object with a metallizing medium, suspending the coated object in an electro-metal bath to form a shell, and backing up said metal shell.

2. The method of producing an embossed replica of an object on a sheet of paper or the like, which includes saturating the object with a solution of gutta percha and bi-sulphite, filling in any undercuts on said 110 saturated object, coating the surface of the object with a metallizing medium, suspending the coated object in an electro-metal bath to form a shell, backing up said metal shell to form a female die, pressing a relatively 115 softer sheet of material into said female die to form a male die, and pressing said male and female dies together with the sheet to be embossed arranged between them.

3. The method of forming a die from an 120 object, which consists in saturating the object with a solution to fill the interstices therein, filling in any undercuts on said saturated object, coating the surface of the object with a metallizing medium and suspend- 130

ing the coated object in an electro-metal bath to form a shell.

4. The method of producing an embossed replica of an object on a sheet of paper or the like, which includes saturating the object with a solution adapted to fill the interstices therein, filling in any undercuts on said saturated object, coating the surface of the object with a metallizing medium, suspending the coated object in an electro-metal bath to form a shell, backing up said metal shell to form a female die, pressing a relatively softer sheet of material into said female die to form a male die, and pressing said male and female dies together with the sheet to be embossed arranged between them.

5. The method of producing dies from an object, which includes forming a metal shell on said object, backing up said metal shell to form a female die and pressing a relatively softer sheet of metal into said female die to form a male die. 20

6. The method of producing dies from an object, which includes filling in any undercuts on said object, forming a metal shell on said object to produce a female die, and pressing a relatively softer material into said female die to form a male die. 25

In testimony whereof, I have signed my name to this specification this 23rd day of 30 August, 1923.

JOHN T. A. PADDENBURG.
